UNITED STATES PATENT OFFICE.

JAMES H. CUSHING, OF SOUTH WEYMOUTH, MASSACHUSETTS, ASSIGNOR TO UNITED SHOE MACHINERY COMPANY, OF PATERSON, NEW JERSEY, A CORPORATION OF NEW JERSEY.

STITCH-SEPARATING MACHINE.

1,229,237.

Specification of Letters Patent. Patented June 12, 1917.

Application filed October 2, 1916. Serial No. 123,321.

To all whom it may concern:

Be it known that I, JAMES H. CUSHING, a citizen of the United States, residing at South Weymouth, in the county of Norfolk 5 and State of Massachusetts, have invented certain new and useful Improvements in Stitch-Separating Machines; and I do hereby declare the following to be a full, clear, and exact description of the invention, such 10 as will enable others skilled in the art to which it appertains to make and use the same.

This invention relates to stitch separating machines, which are now commonly used in 15 the manufacture of boots and shoes to indent the intervals between the stitches appearing upon the upper surface of the projecting edge of the sole, or to shape the crowns of the stitches.

20 It has been discovered in using the commercial machine, which in its general features of construction is built in accordance with Letters Patent of the United States to John B. Hadaway No. 543,012, granted July 25, 1895, that on the return stroke of the feed slide there is some danger of the tool being deflected from its vertical position by reason of contact with the shoe, or a slipping of the friction due to vibration of the machine, or possibly some other cause. The 30 vertical position of the tool should be maintained as a deflection interferes with its proper operation in finding the stitch interval before the feed movement takes place, and also interferes with the feeding stroke.

The object of the present invention is to 35 overcome the defect just adverted to. In accordance with this object it is contemplated to provide the tool-stock with a 40 steadyng or locking device which will prevent an accidental deflection of the tool from its vertical position while on its return stroke after the feed has taken place.

To the accomplishment of the above object, and such others as may hereafter appear as will be understood by those skilled in the art from the following description, the invention comprises the features and combinations of parts hereinafter described 50 and then particularly pointed out in the appended claims.

The preferred form of the invention is

illustrated in the accompanying drawings, in which:

Figure 1 is a front elevation of the machine described in the patent to John B. Hadaway No. 543,012 heretofore mentioned as improved by the later Hadaway Patents No. 719,584, February 3, 1903, and No. 933,174, September 7, 1909, the parts being 60 shown in the positions which they assume at the end of the feeding stroke of the tool and after the tool has been raised from the shoe, and

Fig. 2 is a front elevation showing the 65 parts with the tool just entered in the work at the commencement of a feeding stroke.

In the embodiment of the invention illustrated in the drawings no material change has been made in the general construction 70 and mode of operation of the machine illustrated in the patents hereinbefore referred to. The lower work support 2 with its operating mechanism including the locking lever 3; the feed-slide 4 with its operating lever 75 and actuating cam; the presser lever 5 with its operating cam 6; the upper work support 7; the tool-stock 8 with its friction and tool-carrying lever 9 actuated by the spring 10 and trip-lever 11; and all driven through 80 the pulley 12 and its shaft; all may be and preferably are substantially the same as illustrated and described in said patents.

Referring now to the new feature, that is, the mechanism employed to lock the indenting tool 13 in its vertical position on rising from the shoe after the feeding stroke so as to maintain it in this position during the return stroke of the feed slide 4, two new parts 14 and 15 are employed. The part 90 14 comprises a plate, provided with an angular recess 16 (Fig. 2) in its edge toward the tool, mounted on the upper end of a bracket 17 carried on the forward end of the pivot 18 for the tool-stock operating lever 9. The 95 bracket 17 has a tail piece 19 which carries an adjusting screw 20 threaded into the feed-slide. The plate 14, then, maintains a fixed position throughout the operation of the machine and is carried back and forth 100 with the lever 9 by the movement of the feed-slide. The other new part 15 comprises a plate, provided with an angular tongue 21 (Fig. 1) on its edge toward the plate 14

shaped to snugly fit the recess 16, mounted on the upper side of the swinging tool-stock 8. The plate 15, then, has no fixed position but partakes of the angular movements of the tool-stock about its pivot 22 on the lever 9, when the tool 13 is finding the intervals between the stitches.

In operation the plates 14 and 15 have the following co-operative action: Referring to Fig. 2 which shows the tool 13 finding a stitch interval, the trip-lever 11 releases the tool-stock supporting lever 9 and permits the spring 10 to carry the tool toward the shoe. The tool-stock swings downward about the pivot 18, which movement carries the tongue 21 out of the recess 16 where it has been resting, in which connection it will be noted that both the recess and tongue are formed with one angular or oblique side to permit of their being engaged and disengaged by a movement about the pivot 18. After the indenting tool has found the stitch interval, the indentation is made by an operation of the presser-lever 5. The feed slide 4 then moves to the left to carry the shoe forward, after which the trip-lever 11 operates to raise the tool-stock and tool from the shoe preparatory to the movement of the feed slide to the right and a repetition of the operation just described.

Those skilled in the art are aware that the tool should be vertical, or normal to the surface of the shoe on which it operates, when it descends to find the stitch interval, but if it is not directly over a stitch interval the friction by which the tool-stock is held permits it to be deflected and find the interval. In practice, when the presser-lever 5 operates the tool is more often than not in an oblique position relative to the shoe. As described in said patents hereinbefore mentioned, the presser-lever is so constructed and its operation is such that the tool is brought to a vertical position before the feed is completed and is in such position when the trip-lever 11 operates to raise the tool-stock and tool from the shoe.

The function of the plates 14 and 15 is to maintain this vertical position of the tool until the trip-lever 11 again releases the lever 9 to the influence of the spring 10. As the tool-stock rises, with the lever 9 responsive to the pressure thereon of the trip-lever the movement of the tool-stock to the left about the pivot 18 causes the plate 15 to contact with the fixed plate 14. When the lever 9 has reached the limit of its movement to the left the tongue 21 on the plate 15 has been seated snugly in the recess 16 on plate 14 and the position of the plate 14, determined by a preliminary setting-up adjustment of the screw 20, is such that when the plate 15 is firmly seated against the plate 14 the tool 13 is in its vertical position relative to the work. The two plates remain in

engagement with each other until the completion of the return movement of the feed-slide 4 and the interlocking configuration of their meeting edges is such that the tool 13 cannot be turned from its vertical position by contact with the shoe, jarring of the machine or other causes which formerly affected its position.

By means of the novel construction described any angular movement of the indenting tool about its pivot on the tool-carrying lever, during the return movement of the feed-slide, is prevented and the correct position of the tool to correctly find the next stitch interval and properly indent such interval is assured.

The nature and scope of the invention having been indicated and its preferred embodiment having been specifically described, what is claimed as new, is:—

1. A stitch-separating machine, having, in combination, an automatically adjustable indenting tool, means for actuating the tool to indent the work, and means for invariably presenting the tool to the work in a single, predetermined position prior to its indenting stroke whatever its position relative to the work may be at other times in the cycle of operations.

2. A stitch-separating machine, having, in combination, a work support, a vertically and angularly movable indenting tool, means for actuating the tool to indent and feed the work, and means for preventing angular movement of the tool on its return after the feeding movement.

3. A stitch-separating machine, having, in combination, a work support, a vertically and angularly movable indenting tool, means for actuating the tool to indent and feed the work, means for positioning the tool substantially normal to the work at the completion of the feeding movement, and means for maintaining such position during its return to indenting position.

4. A stitch-separating machine, having, in combination, an automatically adjustable indenting tool, actuating means therefor to provide for finding and indenting the stitch intervals, and means for setting the tool in a single, predetermined position prior to each operation of said actuating means.

5. A stitch-separating machine, having, in combination, a work support, means for indenting the stitch intervals and for feeding the work across the work support including an indenting tool movable both vertically and angularly, means permitting angular movement of the tool in finding the stitch intervals, and means for temporarily locking the tool in a position normal to the work between each stitch-interval-finding and indenting operation.

6. A stitch-separating machine, having, in combination, a work support, a vertically

and angularly movable tool-stock, an indenting tool in said tool-stock normally held in a vertical position relative to the work, means permitting the tool to be moved both vertically and angularly in finding a stitch interval, and means for temporarily locking the tool in its normal position on its withdrawal from the work.

7. A stitch-separating machine, having, in combination, a work support, means for feeding and operating on the work including an indenting tool, a vertically and angularly movable tool-stock for said tool, a part bearing a fixed relation to said tool-stock, and a second part on the tool-stock adapted to engage said fixed part as the tool moves away from the work support and lock the

tool-stock against angular movement with the tool in a position normal to the work.

8. A stitch-separating machine, having, in combination, a work support, a vertically and angularly movable tool-stock, an indenting tool sustained in said tool-stock, means for actuating the tool to indent and feed the work, a plate having a recess in its edge toward the tool-stock bearing a fixed relation to said tool-stock, and a second plate carried by the tool-stock having a tongue adapted to engage in said recess on completion of the feeding movement and hold the tool-stock from angular movement while returning to its indenting position.

JAMES H. CUSHING.
